UNITED STATES PATENT OFFICE.

FRANK J. CALLAGHAN, OF CHICAGO, ILLINOIS.

DESIGN FOR A NECKTIE-FASTENER.

SPECIFICATION forming part of Design No. 32,466, dated April 10, 1900.

Application filed March 17, 1900. Serial No. 9,114. Term of patent 7 years.

To all whom it may concern:

Be it known that I, FRANK J. CALLAGHAN, a citizen of the United States, residing at Chicago, in the county of Cook and State of Illinois, have invented and produced a certain new and original Design for a Necktie-Fastener, of which the following, in connection with the accompanying drawings, is a full, clear, and exact specification.

10 In the said drawings, Figure 1 is a perspective view of a necktie-fastener embodying my design. Fig. 2 is a perspective view thereof looking from the opposite side to that presented in Fig. 1. Fig. 3 is an end view, and

15 Fig. 4 is a top plan view.

The leading features of my design consist of the arms A, each terminating at its outer end in a hook B and at its inner end in an eye C, and the bridge portion D, apparently connecting such eyes together.

The arms A are substantially straight and extend outwardly and upwardly from the eyes C, and at the outer end of each of the arms A is a downwardly-extending U-shaped or hook-shaped portion B, formed at an abrupt angle to the arm A, and the free extremity of the U-shaped portion B having an eye or knob-shaped portion b formed thereon.

The bridge portion D is rectangular in appearance and is apparently a continuation of 30 the arms A, whose inner ends appear to be curved downwardly and thence upwardly to form the eyes C and the rectangular bridge D.

When viewed from the end, the arms A incline upwardly and backwardly toward the 35 hooks B, as better shown in Fig. 3, and when viewed from above the arms A appear at an angle to the bridge portion D, both projecting rearwardly from the same side of the bridge portion D, so as to give the article a 40 bowed appearance from end to end when viewed from above.

The entire article appears to be in the form of a continuous narrow strip, having the bends and angles to produce the formation already 45 described.

Having thus described my invention, what I claim, and desire to secure by Letters Patent, is—

The design for a necktie-fastener substantially as herein shown and described.

FRANK J. CALLAGHAN.
